UNITED STATES PATENT OFFICE.

LE ROY W. STEVENS, OF CHICAGO, ILLINOIS.

SPRAYING MACHINE.

Application filed October 8, 1921. Serial No. 506,449.

To all whom it may concern:

Be it known that I, LE ROY W. STEVENS, a citizen of the United States, residing at Chicago, in the county of Cook and State 5 of Illinois, have invented certain new and useful Improvements in Spraying Machines, of which the following is a description.

My invention relates to improvements in spraying machines, intended to be used for 10 spraying wet materials such as concrete, stucco, whitewash, plaster, water-proofing mixtures, or any other suitable or desired liquids.

One of the objects of my invention is to 15 thoroughly disintegrate the materials to be sprayed into a very fine mist and to deliver the same with sufficient force to the object to be treated to thoroughly and completely cover the surface thereof.

Another object of my invention is to 20 deliver or shoot the spraying material without causing excessive wear on the parts of the machine and to prevent the accumulation and building up of concrete or the particular material used, on the parts of the 25 machine. This is done by providing means whereby the material does not come into contact with that part of the machine or apparatus which directly projects or dis- 30 charges the wet material upon the object being treated; or in other words, the wet material when leaving the machine is shot clear thereof. This is accomplished by providing a belt of air or an air trough, onto 35 which the material drops at the discharge end of the machine, and is absorbed thereby and when carried to complete operation, is broken up into a fine spray or mist, and is carried with the force of the air to the object to be treated.

The invention has among its other objects 40 the production of a device of the kind described which is simple, convenient, compact, durable, reliable, efficient and satisfactory for use wherever found applicable. Many other objects and advantages of the construction herein shown and described

will be obvious to those skilled in the art from the disclosures herein given.

To this end my invention consists in the 50 novel construction, arrangement and combination of parts herein shown and described, and more particularly pointed out in the claims.

In the drawings, wherein like reference 55 characters indicate like or corresponding parts,

Fig. 1 is a top plan view of my device; showing the hopper in section.

Fig. 2 is a front elevation of the same; 60

Fig. 3 is a sectional view taken substantially on the line 3—3 of Fig. 1;

Fig. 4 is a side elevation of my device;

Fig. 5 illustrates a side elevation of another modification of my device; 65

Fig. 6 is a front elevation of the same;

Fig. 7 is a sectional view taken substantially on line 7—7 of Fig. 5;

Fig. 8 illustrates another modified form 70 of device; and

Fig. 9 illustrates still another modified form of device.

In the drawings, wherein I have illustrated the preferred embodiment of my invention, there is shown a portable spraying 75 machine that may be strapped to and carried by the workman from place to place as desired. A hopper 1 is provided to receive the material to be sprayed, said hopper being of any desired size and shape, and having a discharge outlet 2 (Fig. 3) at the bottom thereof. A feeding or agitating shaft 3 is arranged adjacent the bottom of the hopper and is provided with pins 4 projecting radially therefrom, and is adapted to aid in feeding and to prepare and partially liquefy the material within the hopper in such a manner that said material will readily drop through the discharge outlet 2.

It is to be understood that the machine is primarily intended to handle a heavy viscous material such as cement or the like and in the claims the term "heavy viscous" is intended to apply to such materials to distinguish them

from dry or free running materials, but where the material to be sprayed is not viscous, or in other words is free-running, such as whitewashing materials, the agitating shaft 3 and pins may be dispensed with if so desired, as in that case the free-running materials will tend to discharge by gravity alone. A door or valve 5 (Fig. 4) operated by a hand knob 6, may be provided in order to regulate or adjust the flow of material through the outlet 2, said valve in the present instance being formed with rack teeth engageable with pinion teeth on the hand knob 6.

15 Adjacent the hopper 1 and secured thereto by any suitable means is a fan casing 7, there being a fan wheel 8 rotatably arranged therein and adapted to force the air therethrough and discharge it from the throat 9, said throat being adjacent to and below the discharge outlet 2 of the hopper. One or more air intake ports 8', (Fig. 1) may be provided for the fan as desired.

20 Projecting downwardly into the throat 9 and leading from the discharge outlet 2 is a spout or lip 10, (Fig. 2) said spout also projecting slightly forwardly of the throat and terminating substantially at the open end thereof.

25 The spout 10 is preferably set into the throat at an angle sloping toward the outer end of the throat in order to provide an easy slope for the outgoing air, and also to direct the air to the lower edge of the spout, whereby the falling material is picked off and carried forward by the rapidly moving air.

30 The throat 9 is preferably enlarged or outwardly beveled at its open end, as at 11, (Fig. 2) for a purpose to be hereinafter described.

35 The air is discharged from the throat at a high rate of speed (preferably about 200 feet per second) and creating a belt of air beyond the throat on which the material dropped from the spout is conveyed to the surface or object to be treated. As shown in Fig. 3, the material as it falls from the spout will fall onto the belt of air shot out by the fan, said air preferably forming a trough for the material, and will also be carried forwardly due to the force or pressure of said air. During the carrying of the material the particles thereof will become to an extent absorbed by the air, so that at a distance of about 18 inches or more from the throat in the particular size and type illustrated, the particles will be so finely divided as to be substantially in the form of a mist and hence will completely and thoroughly cover the surface to be treated.

40 Any form of drive may be provided for rotating the agitator shaft 3, as for instance, a motor 12, and similarly any form of drive

may be provided for the fan 8, as for instance a second motor 13, there being electrical connections 14 and 15 to said motors to drive them. Operating or carrying handles 16 may be conveniently arranged at the sides of the machine, or otherwise whereby the machine may be manipulated during the operation thereof, and a loop 17 (Fig. 4) may be arranged on the machine in order that it may be carried by a belt or the like, strapped about the operator.

45 It is to be understood that the air that is forced through the throat 9 may be conducted thereto in any preferred manner, and that compressed air means may be used in place of the fan shown, if so desired, the particular novelty of this invention lying in the manner of introducing the wet mixture onto a belt of air.

50 It will be seen from inspection that as none of the concrete or other wet material goes through the moving parts of the machine, there will be no wear or similar injury to said moving parts. Furthermore, due to the positioning of the spout at the extreme end of the throat, all of the material will be carried away by the air belt without any possibility of dropping on the sides of the throat, and hence will not build up or cake thereon. It is preferable to employ the spout 10 to conduct the material from the hopper to the throat, because if the material were dropped directly from the hopper into the throat, then the strong current of air would tend to prevent the material from falling through said feed opening, and the material would soon bank up against the upper wall of the spout and throat and clog the machine.

55 In the modification shown in Figs. 5, 6 and 7, the device is shown as mounted upon a wagon or wheel base, there being a bottom or truck portion 20 for carrying the machine and transporting it from place to place, and having a turn-table or bearing portion 21 at its upper end, whereby the sprayer 22 may be rotated in a horizontal plane. A second pivotal connection 23 is provided so that the sprayer may be rotated in a vertical plane, so that therefore a universal pivotal movement of the sprayer is obtained. A latch 24 is provided whereby the machine may be locked in position.

60 In this particular embodiment there is shown a fan 25 driven by a motor 26, said fan having a discharge throat 27. A hopper 28 is provided with a spout 29 substantially similar to the spout 10 previously described and preferably sloping forwardly of the throat 27 in like manner, so that the material dropping through the spout 29 will fall onto a belt of air, the air trough starting from the throat 27 in this same manner as hereinbefore described.

65 In the modification shown in Figure 8

there is shown a fan 30 driven by a motor 31 and mounted upon a suitable base 32. The motor, fan and base may be transported to any desired location and connected to a conduit or tube 33 having a discharge throat 34. A hopper 35 is arranged above the discharge throat 34 and has a spout 36 projecting downwardly and forwardly thereinto, in the same manner and for a like purpose as spouts 10 and 29 previously described.

In the modification shown in Figure 9 there is a hopper 37 having a discharge spout 38 at the lower end thereof projecting forwardly and downwardly of a throat portion 39. Air from any source under pressure is conducted through the conduit 40 and through the throat 39, there being a valved connection 41 for controlling the admission of said air into said throat. In this instance, as in the previously described modifications, the air discharged through the throat 39 under pressure will form a trough or carrier belt for receiving and carrying the particles of material dropped thereonto through the spout 38. By the expression "close to" or "in proximity to" the delivery or discharge end of the machine, I mean at such a point adjacent the discharge end that any drooling or dripping of a comparatively heavy viscous material, like cement, will not occur.

Having thus described my invention it is obvious that various immaterial modifications may be made in the same without departing from the spirit of my invention; hence I do not wish to be understood as limiting myself to the exact form, arrangement, construction and combination of parts herein shown and described or uses mentioned.

What I claim as new and desire to secure by Letters Patent is:

1. In a machine for spraying a heavy viscous material and in combination, and having a discharge throat, means for discharging air from said throat, and means in said throat for dropping said material upon said air current in proximity to the discharge end, whereby the material will not contact with the proximate walls of the machine at the discharge end.

2. In a machine for spraying material and in combination, and having a discharge throat, means for discharging air through said throat, and means for introducing said material at the outermost end of said throat in a direction substantially parallel to the direction of travel of said air.

3. In a machine for spraying material and in combination, and having a discharge throat, means for discharging air through said throat, means for discharging said material at the outermost end of said throat whereby the material will drop onto said air in proximity to the discharge end of said throat, and means for adjusting the

amount of material fed through said last-mentioned means.

4. In a machine for spraying material and in combination, a discharge throat, means for discharging a belt of air under pressure through said throat, and means for introducing said material onto said belt of air parallel thereto at the discharge end of said throat, whereby the particles of material gradually become absorbed by the air currents and separate into a fine spray carried by said air.

5. In a machine for spraying material and in combination, a container for receiving said material and having a discharge outlet, an air chamber adjacent said discharge outlet, means for discharging air through said air chamber, and a duct leading from said discharge outlet of the container and extending into said air chamber and to the discharge end thereof, whereby said material will drop through said duct onto said air belt in proximity to the discharge end of the duct and be absorbed and carried outwardly in spray form thereby.

6. In a machine for spraying material and in combination, a container having a discharge opening therein, an air chamber having its discharge throat below and adjacent said discharge opening, a spout leading downwardly from said discharge opening of the container into said throat and extending forwardly to terminate at the open end of the throat, means for discharging air through said air chamber, whereby a belt of air is discharged from said throat, and means for feeding the material from said container through said spout, whereby said material will drop onto said belt of air in proximity to the discharge end of the duct and be gradually formed into spray thereby.

7. The method of spraying material consisting in agitating and mixing said material, producing a belt of air trough-shaped on its upper surface, and feeding said mixed material upon the belt of air in proximity to the discharge point of the latter.

8. The method of spraying a wet material consisting in discharging air under pressure into the atmosphere in the form of a trough, and discharging said material onto said trough of air at substantially said point of discharge into the atmosphere so that the discharged material will clear the bounding wall of said air-discharging means.

9. In a machine for spraying material and in combination, a container for receiving said material and having a discharge outlet, an air chamber adjacent said discharge outlet, means for discharging air through said air chamber, and a duct leading from said discharge outlet of the container and extending into said air chamber

whereby said material will drop through said duct onto said air in proximity to the discharge end of the duct and be carried away thereby.

5 10. The method of spraying a wet material consisting in discharging air under pressure into the atmosphere in the form of a trough, and discharging said material onto said trough of air so that it will clear the

bounding wall of said air-discharging means.

In testimony whereof, I have hereunto signed my name in the presence of two subscribing witnesses.

LE ROY W. STEVENS.
